UNITED STATES PATENT OFFICE.

ROBERT SIMON, OF WEEHAWKEN, NEW JERSEY.

POWER-LOOM.

SPECIFICATION forming part of Letters Patent No. 286,081, dated October 2, 1883.

Application filed March 20, 1882. (No model.)

To all whom it may concern:

Be it known that I, ROBERT SIMON, of Weehawken, (town of Union,) in the county of Hudson and State of New Jersey, have invented certain new and useful Improvements 5 in Power-Looms, of which the following is a specification.

This invention relates to looms which run with a free lay—that is to say, looms in which 10 the lay is pushed back by suitable mechanism, and then allowed to drop forward of its own gravity for driving up the weft-threads. In looms of this class in ordinary use the lay is pushed back by a double cam keyed to a shaft, 15 one revolution of which will cause the lay to make the movements for two picks, thus allowing one-half the revolution of the cam to a full movement of the lay. When the lay reaches the end of its forward stroke, it re-bounds backward for a certain distance, and 20 its backward stroke is then completed by the cam, which then comes in contact with its actuating-lever. Unless the motion produced by the cam follows exactly the rebounding motion 25 of the lay, an irregular or jarring motion of the lay is the result. As the periphery of the double cam referred to must be so shaped as to effect two full movements of the lay to one rotation of the cam, the curves of the latter are necessarily abrupt and do not produce 30 the desired harmonious movement of the lay under all circumstances. Variation in the speed of the motive power, and slight changes in any of the working parts, whether caused 35 by atmospheric influences or by the wearing away of some of the parts, will destroy the harmony of the rebounding and cam motions of the lay, causing the latter to jar and the loom to produce goods of unequal texture. 40 Furthermore, the irregular wabbling motion of the lay thus caused entails much loss of time, as in consequence thereof the shuttle often remains in the shed and knocks the warp-threads out, being thrown against the threads 45 and stopped by frictional contact therewith.

The object of this invention is to secure a regular and determinate motion of the lay throughout its entire swing, whereby the above-mentioned defects will be obviated.

50 The invention consists, principally, in a cam the periphery of which forms approximately

an involute curve having its outer end slightly bent inward, whereby the movement of the lay in a power-loom may be made to imitate the motion of the lay in a hand-loom.

55

The invention consists, further, in the combination of a cam of the shape described with the lay and intermediate motion-transmitting mechanism.

The invention consists, further, in the combination of a cam of the shape described, the lay, and certain specific motion-transmitting mechanisms, hereinafter described.

The accompanying drawing represents a vertical longitudinal section of a power-loom of 65 my improved construction.

A in the drawing represents the supporting-frame of my improved power-loom, upon which are arranged the lay B and the other working parts in the usual manner.

70

All the parts of the loom, such as the reed, the heddles, the picker-sticks, and the mechanism for gradually moving the fabric forward and winding it upon the cloth-beam, with the exception of the lay, receive their motion from 75 the main shaft C in a similar manner as in other power-looms. The lay B, however, receives its motion from an auxiliary shaft, D, which carries a cam, D', of peculiar construction, said cam being shown clearly in the drawing, and being made in such a form that the movement which it imparts by intermediate transmitting mechanism to the lay corresponds as nearly as possible to the movement 80 of the lay in a hand-loom. The periphery of 85 this cam forms approximately an involute curve, the outer end of which is slightly bent inward. The shape of this cam has been the result of practical experience, and is so proportioned as to follow the rebounding action 90 of the lay after it has struck the last pick, and continue the movement of the lay in backward direction, and then gradually diminish the motion of the lay until it arrives at its extreme 95 backward position, at which point the lay is free to suddenly drop again, so as to strike the next pick and place the same in proper position.

The auxiliary shaft D of the cam D' receives by suitable transmitting gear-wheels a, twice the speed of the main shaft C, so as to 100 make two revolutions to one of the main shaft, whereby a full revolution of the cam is ob-

tained for each movement of the lay. By thus employing one entire revolution of the cam for each movement of the lay, the cam can be so enlarged and shaped as to secure a continuous contact, or nearly so, of the cam with the actuating-lever of the lay, whereby the latter is brought back and retained in its rearmost position without a jar, so as to allow the shuttle to pass through the shed without straining, the lay being then dropped by its own gravity.

By means of the auxiliary cam described, the loom can be run with a speed of one hundred and fifteen to one hundred and twenty picks per minute, and in such a manner that differences in the speed of the motive power will exert no injurious influence upon the quality of the fabric.

The mechanism by which motion is transmitted from the cam to the lay consists of an oscillating treadle, *b*, acted upon by the cam, a bell-crank lever, *e*, a spring-cushioned rod, *d*, connecting said lever and treadle, and a link, *f*, which latter is connected to a fixed arm, *f'*, of the lay, as shown clearly in the drawing.

To the transmitting mechanism just described, as well as to the other usual accessories of the loom, I lay no separate claim, as the essential feature of this invention is in the interposing of an auxiliary shaft with a cam of peculiar construction, revolving at twice the speed of the main shaft between the driving-shaft and the motion-transmitting mechanism of the oscillating lay.

The lay *B* is provided at both ends with shuttle-boxes, preferably of a construction whereby the shuttle *E*, on entering the box, gradually diminishes its speed and comes finally to a stop without running back.

What is claimed as the invention is—

1. The cam *D'*, the periphery of which forms, approximately, an involute curve having its outer end slightly bent inward, substantially as described.

2. The combination of a cam the periphery of which forms, approximately, an involute curve having its outer end slightly bent inward, with a lay of a loom and intermediate devices between said cam and lay, substantially as set forth. 45

3. The combination, with a main shaft, an auxiliary shaft, and intermediate transmitting mechanism between said shafts, whereby the auxiliary shaft may rotate at twice the speed of the main shaft, of a cam on said auxiliary 55 shaft, the periphery of said cam forming, approximately, an involute curve having its outer end slightly bent inward, an oscillating lay, and means for transmitting motion to the lay from the cam, substantially as described. 50

4. The combination of a main shaft, *C*, an auxiliary shaft, *D*, intermediate gearing between said shafts, whereby the auxiliary shaft may rotate at twice the speed of the main shaft, a cam, *D'*, on said auxiliary shaft *D*, the periphery of said cam forming, approximately, an involute curve having its outer end slightly bent inward, a treadle, *b*, a bell-crank lever, *e*, a spring-cushioned rod, *d*, connecting said lever and treadle, an oscillating lay, *B*, having 70 a fixed arm, *f'*, and a link, *f*, connecting said arm *f'* and bell-crank lever *e*, substantially as described. 65

In testimony that I claim the foregoing as my invention I have signed my name in presence 75 of two subscribing witnesses.

ROBT. SIMON.
